UNITED STATES PATENT OFFICE

HOMER WALTER JONES, OF JACKSON HEIGHTS, NEW YORK, ASSIGNOR TO NATIONAL CARBON COMPANY, INC., A CORPORATION OF NEW YORK

FOCUSING HAND LAMP

Application filed March 31, 1926. Serial No. 98,806.

This invention relates to battery hand lamps, flashlights and similar electric lighting devices, and particularly to improved means for more accurately locating the central part of the lamp filament in the focal axis of the reflector.

The filaments of small incandescent bulbs used in hand lamps and flashlights are often located eccentrically to the longitudinal axis of the bulb, and there are sometimes slight inaccuracies in the parts which carry the lamp and reflector. As a result, it is often a practical impossibility to locate the filament concentrically with respect to the focal axis of the reflector, to be able to obtain a uniform concentrated light beam.

One object of this invention is to provide means for compensating for such non-uniformity in the parts of a battery hand lamp, so that the lamp filament may be positioned symmetrically with respect to the focal axis of the reflector. This is accomplished by mounting the reflector or the lamp so that either one may be adjusted laterally to position the reflector axis so that it passes through the center of the filament.

A further object of this invention is to provide a means for alining the reflector axis and filament, in combination with means whereby the lamp filament may also be adjusted in opposite directions along the reflector axis, to project a uniformly diffused or concentrated light beam, as desired.

The above and other objects and the novel features of this invention will be apparent from the following description taken with the accompanying drawings in which:

Fig. 1 is a longitudinal sectional view of a battery hand lamp embodying this invention; and

Fig. 2 is a horizontal sectional view taken on the line 2-2 of Fig. 1.

Referring to the drawings, C designates a tubular casing of metal or fiber adapted to contain the battery B of dry cells which furnishes current to light the incandescent lamp L having a filament L', which in many lamps is not disposed concentric with the longitudinal axis of the lamp. A threaded metal cap K is adjustably coupled to and closes

the rear end of the casing C and carries a conductive shell 10 therein which engages the zinc bottom of the lowermost cell in the battery B and serves as a supporting abutment for the latter to hold the center electrode B' against the contact 11 carried by the lamp holder H. The front end of the casing is expanded and threaded, as at 12, to receive a similarly threaded removable sleeve F which is also threaded at 14 to take the threaded skirt 15 of a lens ring N which clamps a lens or cover glass E and a reflector R against an annular insulating washer 16 that seats on an in-turned abutment flange 17 forming the outer extremity of the sleeve F.

The lamp L projects through a central aperture 18 in the reflector and has the usual threaded base that is screwed into the metal lamp holder H which is adjustable in opposite directions along the axis of a tubular metal support and guide G. The holder has collars 19, 20 at its opposite ends forming a long bearing therefor, the collar 19 engaging an interior bead or shoulder 21 in the guide G to limit the inward movement of the holder and lamp. A helical spring S is disposed between the holder and guide and has one end seated against a bearing 22 that engages the bead 21 and its opposite end bears against the collar 20. When the cap K is rotated to adjust the holder H and lamp L forwardly, the spring S is compressed, the battery B being guided along with the holder as it is clamped between the cap and the holder. Rotation of the cap in the reverse direction, releases the pressure on the spring and permits it to expand and move the holder H rearwardly, the rearward movement being limited by the rib 21 which also prevents the accidental removal of the parts from the guide when the battery is removed from the casing. The current from the electrode B' may be conducted to the center lamp contact through the contact 11, a plate 22 and a spring contact 23, all secured to the holder H and insulated therefrom by insulating discs 24.

The reflector and lamp holder are supported independently of one another, so that the reflector and cover glass may be removed as a unit for repairs or cleaning without disturb-

ing the lamp and lamp holder; and so that a new lamp may be inserted without touching the reflecting surface of the reflector. The guide which carries the lamp holder is accordingly mounted in the casing independently of the sleeve F which carries the reflector and lens. Moreover, the guide is mounted so that it may be adjusted laterally in any direction to place the filament of the lamp symmetrical with the focal axis of the reflector. During this lateral movement, the lamp holder axis is at all times substantially parallel to the focal axis of the reflector. As shown, the guide is carried by an insulating tube T fitting in and projecting beyond the enlarged part 12 of the casing, the inner end of the tube being seated on a shoulder 25 and secured to the casing by an inward projection 26 of the latter.

The skirt 27 of a retaining ring D is secured to outside of the tube T near its outer end, the outer end of the ring being provided with an inwardly facing groove 28 formed in part by an inwardly projecting abutment or flange 29 that overhangs and is spaced from the end of the tube T. The guide G has an outward flaring part 30 that merges into a cylindrical part 31 formed with an out-turned flange 32 which projects into the groove 28 and abuts against the flange 29. The size of the reflector aperture 18, the width of the flange 32 and the depth of the groove 28 are such that the guide is laterally adjustable a sufficient amount in any direction to position the lamp filament in the focal axis of the reflector.

Suitable means may be provided to effect the desired lateral adjustment of the guide and the lamp holder carried thereby. As shown, screws 33 are threaded into holes 90 degrees apart in the skirt 27 of the retaining ring D and have their inner ends seated in recesses 34 in the wall 31 of the guide G. Holes 35 may be formed in the sleeve F so that a screwdriver may be inserted to turn the screws. Two springs 36, 36 diametrically opposite the screws 33, 33 keep the guide G in contact with the screws in any adjusted position. The screws and springs exert pressure radially or perpendicularly to the focal axis 50 of the reflector. These springs may be set in depressions 38 in the wall 31 and in holes 39 in the tube T. A suitable switch W connected to the guide G by a conductor 40 is operable to control the flow of current through the lamp.

From the foregoing, it will be apparent that the lamp L may be laterally adjusted in any direction by adjusting one or both screws as required, so that the lamp filament will lie in the focal axis of the reflector, permitting the narrowest possible reflected light beam to be obtained from a given lamp. In any of its adjusted positions, the lamp may also be adjusted longitudinally of the reflector axis to position the filament at the reflector focus 60 or in front or back of the same. When a new

lamp is inserted in the holder H to replace a damaged one, the reflector and lens assembly may be removed as a unit by unscrewing the sleeve F, thus avoiding touching the reflective surface. The latter may be cleaned without disturbing the lamp holder assembly. 70

It will be understood that the details of construction herein disclosed may be altered in various particulars without departing from the principles of the invention. 75

I claim:

1. A battery hand lamp comprising the combination of a casing; a reflector having an aperture; an incandescent lamp projecting through said aperture; a support for said lamp mounted in said casing independently of said reflector; a contact on said support in circuit with said lamp; a battery having a center contact engaging the contact on said support; means for adjusting said support in any direction transversely of the focal axis of said reflector, said contacts being maintained in engagement during such adjustment; said means for adjusting said support comprising screws within said casing spaced 90 degrees apart about said reflector axis, and said casing comprising a sleeve carrying said reflector and having holes through which said screws are exposed. 85

2. A battery hand lamp comprising the combination of a casing; a sleeve mounted on said casing; a reflector carried by said sleeve and having an aperture; a tube carried by said casing inside said sleeve; an incandescent lamp projecting through said reflector aperture; a support for said lamp adjustably mounted on said tube; a battery bearing against said support and in circuit with said lamp; and means carried by said tube whereby said support is adjustable in any direction transversely of the focal axis of said reflector. 100

3. A battery hand lamp according to claim 2, wherein said tube carries a grooved part, and said lamp support has a flanged part fitting said grooved part. 110

4. A battery hand lamp comprising the combination of a casing; a sleeve removably mounted thereon; a reflector carried by said sleeve; an annular insulating member carried by said casing inside said sleeve; a guide mounted on said insulating member; a lamp holder adjustable along said guide; an incandescent lamp carried by said holder; and means whereby said guide and reflector are relatively adjustable transversely of the focal axis of said reflector. 115

5. A battery hand lamp comprising the combination of a tubular casing; a battery therein; a sleeve removably mounted on said casing; a reflector carried by said sleeve and having an aperture; an insulating tube secured to said casing inside said sleeve; a guide adjustably mounted within said tube; a lamp holder axially slidabale in said guide; 125

an incandescent lamp carried by said holder and projecting through said aperture; means whereby said lamp holder and lamp are adjustable longitudinally of the focal axis of said reflector; and means whereby said guide with said holder and lamp are adjustable transversely of the focal axis of said reflector.

5 6. A battery hand lamp comprising the combination of a casing; a battery therein; a reflector having an aperture; an adjustable incandescent lamp mounted in said casing and projecting through said aperture; means whereby said lamp is adjustable longitudinally of the focal axis of said reflector; and means within said casing whereby said lamp is adjustable transversely of said focal axis,

10 said casing having an aperture, and such transverse adjusting means being accessible from the outside of said casing through said

15 aperture.

20 7. A battery hand lamp comprising the combination of a casing; a battery therein; a reflector having an aperture; an adjustable incandescent lamp mounted in said casing and projecting through said aperture; means whereby said lamp is adjustable longitudinally of the focal axis of said reflector; and means within said casing whereby said lamp is adjustable transversely of said focal axis,

25 said casing being tubular and containing a cylindrical battery in circuit with said lamp, the circuit connection between one pole of said battery and one terminal of said lamp being maintained intact during all adjustments of said lamp relatively to said reflector.

30 8. A battery hand lamp comprising the combination of a casing; a reflector having an aperture; an incandescent lamp projecting through said aperture; a support for said lamp adjustably mounted in said casing independently of said reflector; a contact on said support in circuit with said lamp; a battery in said casing having a center contact engaging the contact on said support; means

35 for adjusting said support in any direction transversely of the focal axis of said reflector; and means for adjusting said support longitudinally of said focal axis, said contacts being maintained in engagement during

40 such transverse and longitudinal adjustments.

50 In testimony whereof, I affix my signature.
HOMER WALTER JONES.
